UNITED STATES PATENT OFFICE.

JUDSON HAYWARD, OF NEW YORK, N. Y.

HOISTING AND CONVEYING APPARATUS.

No. 811,144.

Specification of Letters Patent.

Patented Jan. 30, 1906.

Application filed March 25, 1905. Serial No. 251,966.

To all whom it may concern:

Be it known that I, JUDSON HAYWARD, a citizen of the United States, and a resident of New York, in the county of New York and 5 State of New York, have invented certain new and useful Improvements in Hoisting and Conveying Apparatus, of which the following is a specification.

This invention relates to hoisting and conveying apparatus, and has particular application to a cable and improved means for hoisting, lowering, opening, and closing a load-carrier, such as a bucket or similar receptacle.

15 My invention consists of the construction, combination, and arrangement of parts set forth in and falling within the scope of the appended claims.

In the accompanying drawings, wherein I 20 have shown one embodiment of my invention, like characters of reference indicate like parts in all the figures, and while I have shown one preferred embodiment of my invention I wish it to be understood that I do not limit 25 myself to the precise details of construction which for the purpose of illustration I have delineated.

Figure 1 is a top plan view of an apparatus provided with my improvements. Fig. 2 is a 30 side view of the same. Fig. 3 is a view in side elevation of my improved hoisting-drum, a portion of the periphery of the drum being broken away to show the location of the band-brake. Fig. 4 is a top plan view of a 35 drum such as shown in Fig. 3. Fig. 5 is a view in side elevation of that part of the friction-drum adapted to carry the closing-line of the bucket, such view showing the location of the friction-surfaces of the clutch mechanism. Fig. 6 is a modification showing another way of holding the closing-line in contact with the surface of the wheel. Fig. 7 is a detail view, in side elevation, of a form of 40 clam-shell bucket in connection with which my invention may be employed. Fig. 8 is a 45 similar view showing the bucket closed.

In the drawings I have shown my invention applied and used in connection with what is ordinarily known as a "clam-shell" bucket, 50 such as is usually employed in dredging or similar operations. As such buckets are now operated it is necessary to provide an extra drum on the engine—that is to say, one drum is required for the holding-line and a second

separate drum for the bucket-closing line. 55 With my invention, however, I dispense with one of the engine-drums and its connections and provide a means whereby either or both the lines of the bucket may be hauled in or paid out, as required. 60

Referring now to the accompanying drawings in detail, the letter A indicates a platform of the apparatus, which may be of any suitable or approved character and upon which is mounted a hoisting-engine B of any 65 well-known type.

C is the drum of the hoisting-engine, around which is wound and secured one end of the closing-line 5.

D is a derrick-frame comprising the upright d and the two inclined standards or struts d', such frame being preferably in the well-known triangular form. 70

The hoisting-boom is shown at E and is connected with the apex of the derrick-frame 75 through the medium of the link-bars e e'.

The load-carrying receptacle, which in the present case is in the form of a clam-shell bucket, is shown at F and is provided with two ropes, that at 5 being termed the "closing-line" and that shown at 6 the "holding-line." The holding-line is fastened at one end, as at 7, to the frame of the bucket and passes over a small sheave-wheel 8 at the outer end of the boom, and thence over a second sheave-pulley 9, suspended from the derrick-frame, to the rope-operating drum G, which drum forms the principal feature of my invention. 80

The bucket herein shown is what is commonly known as the "double chain" or "rope" bucket and is shown in detail in Figs. 7 and 8. This bucket comprises the two sections f f', connected by the central shaft 10, upon which is mounted a power-wheel 11, to which wheel is made fast one end 85 12 of the holding-line 5. 90

13 represents the operating-chains of the bucket, through the means of which the sections of the bucket are brought together, as is shown in Fig. 8, by winding such chains around small pulleys arranged alongside the power-wheel when such power-wheel is turned or actuated by the closing-line 12. 100

14 are the connecting-links of the 105 bucket, which secure such sections to the head-block 15. It is to this block 15 that one end of the holding-line 6 is secured, and

such block is provided with a small idler 16, against which the closing-line 5 bears. The closing-line 5 passes from the power-wheel 11 up past this idler 16, over a sheave 17 at the 5 end of the boom E, thence over the pulley 18 on the derrick-frame to rope-drum G, and thence back to the engine-drum C, to which it is secured.

In order to operate the closing-line 5 and 10 the holding-line 6 for the purpose of raising and lowering and opening and closing the bucket and to avoid the use of an additional drum for the purpose, I have devised the following mechanism:

15 G is a hoisting-drum, which may be located at any point adjacent to the engine, and comprises a frame 20, having the side members 21, in which members is journaled the horizontally-disposed drum-shaft 22. Mounted upon this shaft is the drum, which is in the nature of a two-part friction-drum, such parts being shown at g and g'. The part g, which is relatively longer than the part g', is mounted to turn with and to slide upon the 25 drum-shaft, and in addition to the barrel portion 23, around which is wound the holding-line 6, it is provided with friction-flange 24, having the friction-surface 25 formed with grooves adapted to receive the friction-plates 26 on the face of the part g'. The friction part g' is of less width than the part g and the closing-rope 5 is wrapped around the same, as is shown at 27, such rope then extending back to the engine-drum C, as hereinbefore described.

30 H is a band-brake encircling the flange 25^a of the drum part g, and the ends of such band are connected to the brake-cam 28 at the points 29 29. The foot-lever, as at 30, is connected to the cam in such manner that by depressing such lever the band may be applied to the periphery of the friction-flange. The part g of the drum G is also formed with a second flange 29^a at the opposite end of the barrel from the flange 25^a, and the flange 29 is provided with a circular gear-rack 30, adapted to mesh with the small pinion 31, mounted upon the extension 32 of the support 21, such pinion being actuated through 45 the medium of a small crank 33 for the purpose hereinafter described.

50 The operation of my improvement is substantially as follows: Assuming the bucket to be closed and to be elevated into the position shown in Fig. 2, if it be desired to operate the apparatus for the purpose of conveying a load I proceed in the following manner: The part g of the drum is thrown into frictional engagement with the part g' through 55 the medium of the operating-screw 34, which is provided with a lever 35, and with both the sections thus locked they are lowered by the drum C until the bucket is over the material to be conveyed. The band-brake H is then applied to the section G to hold the same

against movement, and the two parts of the drum g and g' are disconnected or shifted out of engagement. The line 5 is then paid off by the drum C of the engine, thus revolving the part g' until the bucket is opened. Permitting both lines to run loose, the bucket is then lowered into the material, the brake having been removed from the drum-section g for the purpose of allowing the holding-line to run out at the same time with the closing-line. In order to close the bucket upon the material, the drum g', which is now running loose upon its shaft, is turned in the reverse direction by taking up the line 5 on the drum C until the bucket is fully closed, and then 80 the two sections g and g' are again connected through the medium of the friction device, so that by continuing to haul in with the drum C of the engine both the lines will be simultaneously wound about the drums to which 85 their ends are respectively connected until the bucket is elevated to the desired point. Both lines being thus hauled in, to open the bucket and deposit the load it is only necessary to disconnect the two drum-sections g and g' and apply the brake-band to the section g to hold the same stationary and pay out the line 5 with the drum C, which will permit the bucket to be opened by gravity, and the load will be dumped.

90 In some instances when the bucket is seizing a load the sections of such bucket will close upon opposite sides of a hard or lumpy substance, such as a log or the like, and in order to release the grip of the bucket upon 100 this obstacle it is only necessary to release the friction of the drum C to permit the line 5 to slacken slightly, which will cause the sections of the bucket to open to the desired degree, and by turning the pinion 31 by means 105 of the crank 32 the drum-barrel g will be rotated to haul in upon the line 6, and thus the bucket will be elevated sufficiently to clear the obstruction. The operation of closing the bucket by means of the closing-line may 110 then be continued, as described.

115 In Fig. 6 I have shown a modification of a manner of holding the closing-line 5 in contact with the section g' of the hoisting-drum. In such case instead of taking a wrap entirely 120 around the barrel of the section g', as is shown in Fig. 5, I provide a pair of sheaves 36 36, arranged near the lower part of the section, as is shown in Fig. 6, so that the rope 5 may be guided between the same and the 125 drum-section.

130 The many advantages incident to the construction just described will be readily apparent to those skilled in the art. It will be observed that the holding-line, which is attached to the head-block of the bucket, may be employed for maintaining such bucket in a stationary position when the closing-line is released to permit the opening of the bucket or to close the same in taking a load.

While in the drawings I have shown my improved drum mounted upon the body of the frame adjacent to the engine, it will of course be understood that it will be arranged 5 at any suitable point and may be of any preferred character.

What I claim is—

1. The combination of a receptacle adapted to be opened and closed, a holding-line 10 supporting said receptacle, a closing-line, a drum member to which said holding-line is secured, a second drum member around which the closing-line is wrapped and a third drum member to which one end of the closing-line is secured. 15

2. The combination of an engine, a load-receptacle adapted to open and close, a holding-line for said receptacle, a line connected to the engine for closing said receptacle, and 20 means for maintaining the holding-line against movement while paying out on the closing-line to permit the opening of the receptacle, said means comprising two drum members around one of which is wrapped the holding-line and around the other of which is wrapped the closing-line, said closing-line extending back to the engine as aforesaid. 25

3. The combination of a receptacle adapted to open and close, a closing-line connected 30 with the operating mechanism of the receptacle, a drum for actuating said closing-line, a second drum member interposed between the receptacle and the first-mentioned drum and around which the closing-line is wrapped, 35 and a holding-line for said receptacle.

4. The combination of a receptacle adapted to open and close, an engine, a two-part friction-drum between the engine and the receptacle, a holding-line supporting said receptacle and having an end portion secured to one part of the friction-drum, a closing-line 40 connected to said receptacle, and passing about the other part of said friction-drum and having an end secured to the engine, and 45 means for engaging and disengaging the two parts of said friction-drum.

5. The combination of a receptacle adapted to open and close, an engine, a friction-drum between the engine and receptacle, a 50 holding-line connected to said receptacle and to the friction-drum, and a closing-line extending from the receptacle to the drum and thence to the engine.

6. The combination of an engine, a load-receptacle adapted to open and close, a line 55 connected with the operating mechanism of the receptacle, a holding-line connected to the head of said receptacle, a two-part friction-drum to which both of said lines are connected, means for throwing the parts of said drum into and out of engagement, to actuate both of said lines simultaneously, and at different times, respectively, braking mechanism for holding one of said drum parts 60 against movement, and a third drum to

which one end of the first-mentioned line is connected.

7. The combination of an engine, a two-part friction-drum, a load-receptacle, a supporting-line extending from the receptacle to one part of the friction-drum, a closing-line 70 extending from said receptacle to the other part of said drum and thence to the engine, means for throwing the two parts of the drum into and out of engagement to operate 75 said ropes simultaneously and at different times, respectively, and supplemental mechanism for actuating one part of said drum independent of the other part and of the engine. 80

8. The combination of an engine, a two-part drum, a load-receptacle, a supporting-line connected to said receptacle and to one part of said drum, a closing-line extending from the receptacle to the other part of said 85 drum and thence connecting said second part of the drum with the engine, means for connecting said drum parts to cause both to be driven simultaneously with the engine, and independent means for actuating one part of 90 said drum independent of the other.

9. The combination of a frame, including a boom, an engine for said frame, a load-receptacle at one end of the boom, a supporting-line connected to said receptacle and passing 95 over the boom, an actuator to which said supporting-line is secured, and a second line extending from said receptacle to the boom thence to the actuator and thence to the drum of the engine. 100

10. The combination of an engine, a sectional bucket, mechanism for operating said sections, an actuator located between the engine and said receptacle, a line extending from the operating mechanism of the bucket 105 to said actuator and thence to the engine, and a second line connecting the frame of said bucket with the actuator.

11. The combination of a sectional bucket, and means for operating said bucket to permit the opening and closing of same comprising an engine, a drum member and a line extending from said engine to the drum member and thence to the operating mechanism of the bucket. 115

12. The combination of a receptacle, an engine, an actuator comprising a two-part drum, a line extending from said receptacle to one part of the drum and secured thereto, a second line extending from the receptacle 120 to the other part of said drum and thence to the engine, means for engaging and disengaging the parts of the drum, and means connected to one section of the drum for rotating the same independent of the other, such 125 means comprising a rack-and-pinion mechanism.

13. The combination of a receptacle, an engine, a two-part friction-drum, means for engaging and disengaging the parts of said 130

drum, a line extending from said bucket to one part of said drum, a second line extending from said bucket to the other part of said drum and thence to the engine, and means
5 for holding one part of said drum stationary while the other part is driven from the engine to operate its line.

In testimony whereof I have signed my name to this specification in the presence of two subscribing witnesses.

JUDSON HAYWARD.
